CHAIR

Leon G. Miller, Cleveland, Ohio, assignor to The Taylor Chair Company, Bedford, Ohio, a corporation

Filed Feb. 2, 1960, Ser. No. 59,229

Term of patent 14 years

(Cl. D15—1)

The dominant features of the design reside in the portions shown in full lines on the drawings, the essential characteristics of which reside in upraised and separately defined upholstered seat, back rest, and arm rest portions contrasting with exposed panel frame portions, substantially as shown.

I claim:

The ornamental design for a chair, as shown and described.
